UNITED STATES PATENT OFFICE

RALPH COHEN, OF GALION, OHIO, ASSIGNOR TO PERFECTION STEEL BODY CO., OF GALION, OHIO, A CORPORATION OF OHIO

DESIGN FOR A BURIAL VAULT

Application filed May 31, 1932. Serial No. 43,933. Term of patent 14 years.

To all whom it may concern:

Be it known that I, RALPH COHEN, a citizen of the United States of America, residing at Galion, in the county of Crawford and State of Ohio, have invented a new, original, and ornamental Design for a Burial Vault, of which the following is a specification, reference being had to the accompanying drawing, forming a part thereof.

In the drawing:

Fig. 2 is an end view of the same.

I claim:

The ornamental design for a burial vault, as shown.
